CHARLES S. DEMAREST, OF BROOKLYN, NEW YORK, ASSIGNOR TO AMERICAN TELEPHONE AND TELEGRAPH COMPANY, A CORPORATION OF NEW YORK.

RINGING ARRANGEMENT FOR FOUR-WIRE CIRCUITS.

1,317,155.

Specification of Letters Patent. Patented Sept. 30, 1919.

Application filed December 2, 1918. Serial No. 265,037.

To all whom it may concern:

Be it known that I, CHARLES S. DEMAREST, residing at Brooklyn, in the county of Kings and State of New York, have invented certain Improvements in Ringing Arrangements for Four-Wire Circuits, of which the following is a specification.

This invention relates to transmission circuits and more particularly to transmission 10 circuits of the type known as four wire circuits.

The principal feature of this invention consists in an arrangement at the junction point of a two wire system and a four wire 15 system whereby a ringing current of a definite frequency incoming from either system may be relayed to the other system. This result is accomplished by providing a ringing responsive relay in each of the one-way 20 paths comprising the four wire circuit at the junction point of the four wire circuit and the two wire circuit in such a manner that both relays will respond to incoming signaling current from the two wire circuit 25 to switch a local source of signaling current to the outgoing path of the four wire circuit while but one relay responds to signaling current incoming from the four wire circuit and functions to apply the relayed source of signaling current to the two 30 wire circuit.

One of the relays is rendered unresponsive to signaling current incoming from one path of the four wire system by reason of the fact that the two wire circuit is balanced by an artificial line. Another feature of the invention has reference to the provision of means whereby this balance may be maintained when the two wire line is disconnected from the junction during its connection to the relayed source of signaling current thereby preventing a false operation of the relay.

Other and further objects of the invention 45 will be clear from the following description when read in connection with the accompanying drawing the figure of which constitutes a circuit diagram of so much of the system as is necessary to an understanding 50 of the invention.

Referring to the drawing a four wire circuit is shown comprising two wire lines L_E and L_w for transmission in opposite directions said two wire lines being associated 55 with the terminating two wire circuit L

through a three-winding transformer 1. The diagram illustrates the apparatus at one station only of the system but it will be understood that the four wire circuit comprising paths L_E and L_w extends to a distant station at which a similar junction arrangement for a terminating two wire line is provided. The two paths L_E and L_w of the four wire circuit may be provided with one-way repeaters at suitable intervals 60 along the line in order to provide the desired gain in transmission. The apparatus so far described is of the general type illustrated in the application of George A. Campbell, Serial Number 72,606, filed January 17, 1916, and a full illustration of the theory and operation of a four wire circuit may be had by reference to said application. 70

In order to relay ringing current in accordance with this invention two ringing responsive relays 2 and 3 are provided, the former being associated with the path L_w and the latter being associated with the path L_E . The line L is balanced with respect to the incoming path L_w by means of an 80 artificial line N so that the relay 3 is unresponsive to current transmitted from the path L_w . Both relays 2 and 3 are responsive to current incoming from the two wire line L and control arrangements whereby ringing current from source 4 of the same frequency as that incoming from the line L may be applied to the outgoing path L_E of the four wire circuit. The relay 2 responds 85 to ringing current of this frequency incoming from the path L_w to apply the source 4 to the two wire line L . In order to prevent an unbalance of the system due to the fact that the line L is disconnected from the junction during this operation means is provided whereby an auxiliary net work N' is substituted for the line L . This prevents the relay 3 from being actuated by ringing current from the path L_w which might be impressed upon said relay due to the unbalanced condition of the circuit with respect to the artificial line N . 90 95

The operation is as follows: Signaling current incoming from the line L flows over conductors 5 to points 6 and 7 where the 100 current divides part flowing through the bridge circuit including the autotransformer 8 to actuate the relay 2. The current flowing over conductors 5 and in series through the transformer 1 acts only to actuate the 105 110

ringing responsive relay 3. Relay 2 upon being energized opens the circuit of a normally energized relay 9 while relay 3 removes a short circuit about the winding of relay 10. Relay 9 upon being deenergized completes a circuit for the relay 11 which sets the generator 4 into operation to generate alternating current of the desired frequency, which in practice may be in the neighborhood of 133 cycles. Relay 9 upon being deenergized also completes a circuit from ground over its back contact and through the winding of relay 10 to battery. Relay 10 closes a circuit from ground over the back contact of relay 9 front contact of relay 10 through the winding of relay 12 to battery. Relay 12 disconnects the path L_w from the circuit 13 and connects it to conductors 14 leading to the generator 4 so that ringing current from said generator is applied to the path L_w and transmitted over one side of the four wire system to the distant station.

Ringing current transmitted from the distant station over the path L_w actuates the relay 2 but owing to the fact that the incoming conductors 15 from said path are bridged across equal potential points 6 and 7 with respect to the artificial line N and the two wire line L the energy applied to points 6 and 7 divides substantially equally between the line L and the artificial line N and as a result no effect is produced upon the relay 3. The relay 2 upon being energized again opens the circuit of relay 9 which at its back contact completes the circuit of relay 11 to set the generator 4 into operation. Since the relay 3 is not actuated the winding of relay 10 is short circuited so that said relay is not actuated. Consequently relay 9 upon being deenergized completes a circuit from ground over its back contact, over the back contact of relay 10 and through the windings of relays 16 and 17 in parallel to battery. Relay 16 disconnects the two wire line L from the junction transformer 1 and connects it to conductors 18 leading to the source of ringing current 4 so that ringing current from said source is transmitted over the line L. The relay 17 upon being energized substitutes an auxiliary net work or artificial line N' for the line L in order to balance the artificial line N during this operation. If this balance were not maintained a portion of the energy incoming from conductors 15 would be transmitted to the relay 3 to cause a false operation thereof.

It will be seen that by means of the above arrangement ringing current may be relayed from one system to another in either direction by placing the relaying apparatus under the joint control of two ringing responsive relays one of which responds only to current incoming from one system and

the other of which responds to current incoming from either system. It will also be obvious that the general principles herein disclosed may be embodied in many other organizations widely different from those illustrated without departing from the spirit of invention as defined in the following claims.

What is claimed is:

1. In a signaling system, a four wire transmission circuit, a two wire transmission circuit, means interconnecting said circuits, a relay responsive to signaling current transmitted from one of said circuits only, a second relay responsive to signaling currents transmitted from either circuit, means responsive to the energization of one of said relays to apply signaling current to one of said circuits, and means responsive to the energization of both of said relays to apply signaling current to the other circuit.

2. In a signaling system, a transmission circuit comprising two paths, one for transmitting in one direction and the other for transmitting in the opposite direction, a second transmission circuit comprising a single path for transmitting in either direction, means interconnecting said circuits, a relay responsive to signaling currents transmitted from one of said circuits only, a second relay responsive to signaling currents transmitted from either circuit, means responsive to the energization of one of said relays to apply signaling current to one of said circuits, and means responsive to the energization of both of said relays to apply signaling current to the other circuit.

3. In a signaling system, a transmission circuit comprising two paths, one for transmitting in one direction and the other for transmitting in the opposite direction, a second transmission circuit comprising a single path for transmitting in either direction, means interconnecting said circuits, a relay responsive to signaling currents incoming from either circuit, a second relay responsive to signaling currents incoming from one of said circuits only, means responsive to the energization of said relay to apply signaling current to the other circuit, and means responsive to the energization of the other relay to apply signaling current to the remaining circuit.

4. In a signaling system, a transmission circuit comprising two paths, one for transmitting in one direction and the other for transmitting in the opposite direction, a second transmission circuit comprising a single path for transmitting in either direction, means interconnecting said circuits, a relay responsive to signaling currents incoming from said second mentioned circuit only, a second relay responsive to signaling currents incoming from either circuit, means responsive to the energization of both said re-

lays to apply signaling current to said first mentioned circuit, and means responsive to the energization of said first mentioned relay alone to apply signaling current to said second mentioned circuit.

5. In a signaling system, a transmission circuit comprising two paths, one for transmitting in one direction and the other for transmitting in the opposite direction, a second transmission circuit comprising a single path for transmitting in either direction, means interconnecting said circuits, a pair of relays associated with said circuits and responsive to signaling currents transmitted thereover, means responsive to the energization of both of said relays to apply signaling currents to one of said circuits, and means responsive to the energization of one of said relays alone to apply signaling current to the other of said circuits.

10. In a signaling system, a transmission circuit comprising two paths, one for transmitting in one direction and the other for transmitting in the opposite direction, a second transmission circuit comprising a single path for transmitting in either direction, means interconnecting said circuits, a pair of relays associated with said circuits and responsive to signaling currents transmitted thereover, means responsive to the energization of both of said relays to apply signaling current to said first mentioned circuit, and means responsive to the energization of one of said relays alone to apply signaling current to said second mentioned circuit.

15. In a signaling system, a transmission circuit comprising two paths one for transmitting in one direction and the other for transmitting in the opposite direction, a second transmission circuit comprising a single path for transmitting in either direction, means interconnecting said circuits, means responsive to signaling current of a definite frequency incoming from one of said circuits to apply current of that frequency to the other circuit, and means responsive to signaling current of the same frequency

incoming from the latter circuit to apply signaling current of that frequency to the first circuit.

20. A transmission circuit comprising a path for transmitting in either direction, an artificial line for balancing said path, a second transmission circuit comprising a path for transmitting in one direction connected to equi-potential points between said first circuit and said artificial line and a path for transmitting in the opposite direction inductively related to said first mentioned path and artificial line, a ringing responsive relay associated with each of said second and third mentioned paths, both of said relays responding to ringing current incoming over said first mentioned path to apply ringing current to one of the other two paths, and one only of said relays responding to ringing current incoming over the remaining path to apply ringing current to said first mentioned path.

25. In a signaling system, a transmission circuit comprising two paths, one for transmitting in one direction and the other for transmitting in the opposite direction, a second transmission circuit comprising a single path for transmitting in either direction, means interconnecting said circuits, means associated with one of the paths of said first mentioned circuit and responsive to incoming currents from said second circuit to relay signaling currents to said path, an artificial line for balancing said second circuit with respect to said means to prevent said means responding to incoming currents from the other path of said first mentioned circuit, means to disconnect said second circuit from said first circuit and apply signaling current thereto, and means functioning during the latter operation to balance said artificial line with respect to said first mentioned means to prevent its actuation.

30. In testimony whereof I have signed my name to this specification this twenty-ninth day of November, 1918.

CHARLES S. DEMAREST.
